UNITED STATES PATENT OFFICE.

MATHEW WESLEY MASHBURN, OF WEDOWEE, ALABAMA.

STUMP-PULLER.

SPECIFICATION forming part of Letters Patent No. 691,645, dated January 21, 1902.

Application filed June 5, 1901. Serial No. 63,301. (No model.)

To all whom it may concern:

Be it known that I, MATHEW WESLEY MASHBURN, a citizen of the United States, residing at Wedowee, in the county of Randolph and State of Alabama, have invented a new and useful Stump-Puller, of which the following is a specification.

This invention relates to apparatus for pulling stumps and lifting and transporting other heavy bodies; and it consists in the construction, combination, and arrangement of parts, as hereinafter shown and described, and specifically pointed out in the claims.

In the drawings, Figure 1 is a side elevation, partially in section. Fig. 2 is a front elevation, and Fig. 3 is a plan view, of the apparatus complete. Fig. 4 is a detached perspective view of one of the removable side-brace sections. Fig. 5 is a perspective view of a section of the lower portion of the lifting-screw and the coupling mechanism, illustrating the construction more fully.

The framework of the apparatus consists of the head timber 1, having four diverging legs 2 3 4 5, connected to its corners, as by bolts 6 and 7, and with shoe-timber 8, connected to the lower ends of the legs 4 and 5, and a similar shoe-timber 9, connected to the lower ends of the legs 2 and 3, as shown. The legs 2 and 3 are connected intermediate of the shoe 9 and head 1 by a tie-bolt 10, and the legs 4 and 5 are likewise connected by a similar bolt 11. The legs 2 and 4 are also connected by tie-rod 12, and the legs 3 and 5 are likewise connected by tie-rod 13, as shown, these tie-rods being disposed above the center of the framework, so as to leave the lower part unobstructed between the corner-posts for the convenience of the operator in attaching the chains to the couplings. Removable transverse tie-rods 14 15 are also arranged to connect the ends of the shoes 8 and 9, as shown, these tie-rods being detachable to permit the apparatus to be placed over the stump or other article to be acted on by the machine.

Inserted into the spaces between the posts 2 and 3 and the shoe 9 and tie-rod 10 is a removable diagonal cross-brace 16, and a similar diagonal cross-brace 17 is disposed in the corresponding space between the legs 4 and 5 and shoe 8 and rod 11, as shown in Fig. 1. These diagonal cross-braces thus serve firmly

and securely to brace the sides of the frame when in place and by being removable will by that means provide for rendering the interior of the framework easily accessible for the purpose of coupling the chains to the article to be acted upon by the machine.

The diagonal cross-braces will preferably be formed with shoulders 18, adapted to engage the tie-rods 10 and 11, so that the tie-rods will serve as stops to limit the inward movement of the braces, and thus support them in position between the posts.

19 represents the lifting-screw, which is of 65 the usual construction and will be provided with a transverse pin 20 through its lower end and will pass upward through the head 1, as shown. Upon the head 1 is a transverse block 21, with a central portion cut away, so 70 that its ends project downward below the sides of the head 1, as shown at 22 in Fig. 2, to insure support against lateral strains. The block 21 and head 1 are each provided with registering central apertures 21^a 21^b for the 75 reception of the screw 19, and the block immediately around this aperture 21^a is concaved. Upon the block 21 is supported a plate 22, having its lower surface convex and its upper surface concaved to correspond to 80 the concave in the block 21, as shown in Fig. 1, to afford a bearing for the nut 24 of the screw 19, the lower surface of the nut being convex to fit the concave side of the plate 23, as shown in Fig. 1.

Clamped upon the sides of the nut 24 by bolts 25 are two blocks 26 27, the blocks having recesses in their adjacent sides to embrace the nut 24 and the screw 19 and also having recesses in their ends to provide for the pivotal engagement of sweeps 28 29, by which the screw may be actuated by revolving the nut and the binding-plates by power applied to the ends of the sweeps.

The apertures 21^a 21^b through the head 1 95 and the block 21 for the screw 19 are considerably larger than the screw, so that the latter will be free to swing by its lower end in all directions without danger of cramping, this free lateral movement being provided 100 for by the coacting corresponding concave and convex surfaces of the block 21 and nut 24, as will be readily understood.

Surrounding the lower end of the screw 19

and supported upon the pin 20 is a preferably oblong or elliptical ring 30, and linked into this ring at its longer ends are hooks 31 32, and surrounding the screw 19 above the 5 ring 30 and resting upon the upper ends of the shanks of the hooks 31 32 is another ring 33, the duplicate of the ring 30, and supporting-hooks 34 35, which are substantially duplicates of the hooks 31 and 32. Thus the 10 four hooks will be supported by the two rings and the two rings supported by the one transverse pin 20. The hooks and rings being substantially duplicates, there will be no danger of getting them mixed or displaced when being placed in position.

In operating the device the usual chains are placed about the stump or stone or other heavy article to be lifted and the tie-rods 14 or 15 and the diagonal cross-braces 16 and 17 15 removed and the machine drawn over the stump or other article to be lifted. The removal of the side braces 16 and 17 and the rods 14 and 15 leaves the screw and its coupling means and the chains about the stump 20 or other article to be lifted free of access, except for the four corner-posts 2, 3, 4, and 5, so that the coupling may be readily and quickly made between the chains encircling the stump or other article to be lifted and the 25 hooks 31 and 32 and 34 and 35. The operator is therefore not hampered or hindered in his work by the presence of obstructions. After the coupling is completed the rods 14 and 15 are connected to the ends of the shoes 30 and the diagonal cross-braces are replaced in position, so that when the power is applied the framework will be effectually braced, so that it will be able to resist the severe strains 35 to which it will be subjected. This makes a 40 very convenient and compact apparatus that

will effectually perform the work required of it and at the same time be applicable for use in locations in which many machines of this class are inoperative.

The construction of the coupling-hooks is 45 an important feature of my invention, as it dispenses with many extra parts and greatly facilitates the operations by its simplicity and efficiency.

What I claim as new is— 50

1. In a device of the class described, a supporting-framework having a central aperture in its upper part and concaved around said aperture, a screw projecting through said aperture, a nut engaging said screw and with a 55 convex surface engaging said concave surface in said framework, two blocks having recesses embracing said nut, and means for clamping said blocks upon said nut, and power-sweeps pivotally connected with said blocks, substantially as shown and described.

2. In a device of the class described, a supporting-framework having a head timber, a transverse block embracing said head and with a central enlarged aperture and having 65 a concaved upper surface around said aperture, a screw projecting through said aperture, a nut engaging said screw and with a convex surface engaging said concave surface, a socketed head-block clamped upon the 70 nut, and sweeps pivotally connected with the block, substantially as shown and described.

In testimony that I claim the foregoing as my own I have hereto affixed my signature in the presence of two witnesses.

MATHEW WESLEY MASHBURN.
